UNITED STATES PATENT OFFICE

PAUL GARRIGUE, OF NEW YORK, N. Y.

COLLAPSIBLE GLOBE

Application filed February 10, 1928. Serial No. 253,283.

This invention relates to collapsible globes, and more particularly to an inflatable globe which may carry on its exterior surface markings of the type usual in globes representing the world used for educational purposes.

It has been proposed to use globes of the type described for convenience in transportation, lightness and other advantages. However, so far as is known to me, none of the collapsible globes heretofore proposed, have been practical from a manufacturing standpoint because the structures so far known have been more or less cumbersome, unreliable, and expensive to manufacture.

10 It is an object of this invention to provide a collapsible globe which is simple and rugged in construction, light in weight, and in which the number of operations necessary for assembling are reduced to a minimum.

15 It is a further object of this invention to provide a practical collapsible globe which may be manufactured and sold at a relatively low cost. Still further objects and advantages of my invention will be apparent from the specification.

The features of novelty which I believe to be characteristic of my invention are set forth with particularity in the appended claims. My invention itself, however, both as to its fundamental principles and as to its particular embodiments will best be understood by reference to the specification and accompanying drawings, in which:

Figure 1 is an elevation of a collapsible globe according to my invention, showing the mounting in section.

Figure 2 is a plan view of the fabric sections of which the collapsible envelope is constructed.

Figure 3 is a diagrammatic view of the base of the envelope with the anchoring ring secured in position.

Figure 4 is an exploded sectional view of the base assembly.

Figure 5 is a perspective view of the anchoring ring according to my invention: and

Figure 6 is a sectional view of a modified form of base plate according to my invention.

In accordance with my invention, I provide a fabric envelope which is preferably

formed of a series of petal-like sections which are sewn or otherwise secured together in the form of a substantially spherical envelope. The petal-like sections are so formed as to leave an opening in the completed spherical envelope of sufficient size to permit the insertion of a bladder into the envelope. Adjacent the opening, I prefer to provide on each of the petal-like sections a small tab which may be folded over and sewed or riveted to form a loop adjacent the opening of the envelope. To provide an anchoring member by means of which the globe may be secured to a base, I provide a ring within the loops already described, the said ring being thereby positioned at the opening in the envelope, and for convenience of manufacture, the ring is preferably split so that it may be readily inserted into the loops, although under certain conditions, the ring may be solid and may be secured in position by folding the tabs over it and then fastening the ends of the tabs. For the purpose of carrying and supporting the inflatable globe, I provide a base plate preferably in the general form and contour to fit the bottom of the globe. This plate is also provided with a central opening through which the bladder may be inserted or withdrawn, and is preferably provided adjacent the central opening with an annular trough to receive the anchoring ring. For the purpose of securing the anchoring ring in position on the base plate, I provide means carried by the base plate which may be in the form of flexible fingers, which may be bent over the ring to secure it in position: and I also provide means on the base plate adapted to receive or cooperate with any desired form of stand or shaft.

Referring now more particularly to Figure 1, 1 designates generally a flexible fabric envelope which may be provided with suitable markings such for example as a map of the world in any desired representation. The fabric envelope 1 is maintained in spherical shape by means of a suitable inflatable bladder 2 positioned therein. The bladder 2 may conveniently be one of the type used in basketballs for example, and has a stem 2a through

which it may be inflated. The envelope 1 is preferably formed by sewing together a plurality of petal-like sections of fabric 4, provided with a selvage edge 5, to allow for a seam, and also carrying at one end a tab 6 for the purpose of securing the flexible envelope to the anchoring ring 8.

It will be noted that the distance from the equator to the base of the tab 6 is less than that from the equator to the opposite end of the section 4, whereby when the sections 4 are sewed together, a polar opening will be left in the envelope 1.

In assembling the envelope, the sections 4 will be sewed together with the seam on the outside, and the tab 6 will be preferably turned over and sewed with the seam on the same side, either before or after the sections are sewed together. The split ring 8 may then be inserted in the loops 7, after which the envelope may be turned inside out through the opening where the ring 8 is positioned, and all seams will then lie on the interior.

As an alternative to the use of a split ring, a solid ring may be used, after which the tabs may be turned over to form the loop 7, and then sewed or riveted in position.

For the purpose of mounting the globe, I provide a base plate 9 having a central opening 10 and an annular trough 11. The base plate 9 will be preferably of a shape and size to fit and support the bottom of the envelope 1, and the trough 11 is provided to receive the anchoring ring 8. The use of such a trough permits a better fit between the base plate and the bottom of the globe, and although I prefer to utilize it, it will be understood that under certain conditions, it may be omitted.

In order to anchor the ring 8 in position on the base plate, I provide means carried by the base plate and embodying preferably flexible fingers, which lie within the ring 8 and may be bent outwardly over the ring to hold it in position. In the preferred form of my invention, there are provided a plurality of flexible fingers 14 carried upon a sleeve 12 provided with a boss 13, of the proper size to fit snugly within the opening 10 in the base plate 9.

After the ring 8 has been positioned within the trough 11, the sleeve 12 may be inserted in the opening 10 until the boss 13 engages the inner edge of the base plate, after which the fingers 14 will project upwardly over the ring 8. These fingers are then bent outwardly over the ring 8 in the manner shown in Figure 1, and pressed downwardly preferably until they lie flush with the projected inner spherical surface of the base plate 9, thereby minimizing the possibility of the bladder being punctured. The downwardly depending sleeve 12 may be arranged to fit upon

any suitable stand by means of a socket joint, bayonet joint or the like, and as the manner of making such connection forms no part of this invention, it is not described in detail.

While I have described one form of my invention, which is preferable under certain conditions, nevertheless modifications may be made: for instance, the globe 1 may be made of eight sections, each section being substantially in the form of a spherical triangle, the angles at the apexes of which are all approximately 90°: also, while I have shown the fingers 14 mounted upon a separate sleeve 12, the base plate 9 and sleeve 12 may be formed integral by suitably drawing the base plate, and the fingers 14 may be punched out from the base plate in any suitable manner, as shown in Figure 6.

It will be noted that an advantage of the construction described is that while the construction is simple and inexpensive, nevertheless the complete globe presents a finished appearance, because all joints are concealed.

While I have shown and described certain preferred embodiments of my invention, it will be understood that I do not wish to be restricted to the precise form shown and described, but that modifications and changes may be made without departing from the spirit and scope of my invention, as will be understood by those skilled in the art.

I claim:

1. In a collapsible globe, in combination, a collapsible envelope having an opening therein, a ring insertable in said envelope, a base plate arranged to receive said ring and extending outwardly from the ring-receiving portion to form a support for the lower portion of said envelope, and means carried by said base plate for securing said ring and said base plate in position, said means comprising a gripping member extending over said ring at a plurality of points.

2. In a collapsible globe, in combination, a collapsible envelope having an opening therein, a ring insertable in said envelope, a base plate arranged to receive said ring and extending outwardly from the ring-receiving portion to form a support for the lower portion of said envelope, and means carried by said base plate for securing said ring and base plate in position, said means comprising flexible fingers bendable over said ring at a plurality of points.

3. In a collapsible globe, in combination, a collapsible envelope having an opening therein, a ring insertable in said opening, a base plate having a central opening therein and arranged to receive said ring and extending outwardly from the ring-receiving portion to form a support for the lower portion of said envelope, and means associated with said base plate for securing said ring and base plate in position, said means comprising fingers engaging said ring on the side

opposite said base plate at a plurality of points.

4. In a collapsible globe, in combination, a collapsible envelope having an opening therein, a ring insertable in said envelope at said opening, a base plate having a central opening, and an annular depression surrounding said opening and arranged to receive said ring and having an envelope supporting portion surrounding said depression, and means associated with said base plate for maintaining said ring in said depression.

5. In a collapsible globe, in combination, a collapsible envelope having an opening therein, a ring insertable in said envelope at said opening, a base plate having a central opening, and an annular depression surrounding said opening and arranged to receive said ring and an envelope supporting portion surrounding said depression; and a sleeve engageable with the opening in said base plate and having a plurality of inwardly projecting fingers bendable outwardly over said ring to maintain said ring in position on said base plate.

25 6. In a collapsible globe, in combination, a collapsible envelope formed of sections of fabric secured together and having a polar opening; and having loops formed in said fabric at said opening; a split ring insertable in said loops; a base plate having a central opening, and an annular ring-receiving trough surrounding said opening; and a collar insertable in said opening in said base plate, said collar being provided with a plurality of spaced upwardly extending fingers bendable over said ring to secure said ring in position in said annular trough.

30 Signed at New York city in the county of New York and State of New York this ninth day of February A. D. 1928.

40 PAUL GARRIGUE.
